UNITED STATES PATENT OFFICE.

JOHN O. LAGERQUIST, OF HAMILTON, MONTANA.

FURNACE-DOOR-OPERATING DEVICE.

SPECIFICATION forming part of Letters Patent No. 780,204, dated January 17, 1905.

Application filed September 23, 1904. Serial No. 225,649.

To all whom it may concern:

Be it known that I, JOHN O. LAGERQUIST, a citizen of the United States, residing at Hamilton, in the county of Ravalli and State of Montana, have invented new and useful Improvements in Furnace-Door-Operating Devices, of which the following is a specification.

This invention is a device for opening and closing furnace-doors quickly and also includes means for holding the door open when desired.

The door is opened by means of foot-pressure on a treadle and is closed by a spring upon release of the treadle, the movement being transmitted by means of gearing and appliances to be hereinafter described.

In the accompanying drawings, Figure 1 is a front elevation of the device. Fig. 2 is a side elevation thereof, parts being shown in section. Fig. 3 is a bottom plan view of the mechanism under the platform.

Referring specifically to the drawings, 6 indicates the furnace-door, and 7 the platform in front of the furnace. 8 indicates a crank, 5 the upper end of which projects under a strap 9, fixed to the furnace-door and the lower end of which extends through the platform, under which it is provided with a bevel-gear 10. This crank swings in a horizontal plane and by its swing opens or closes the door.

The bevel-gear 10 referred to on the lower end of the crank is in mesh with a gear on a shaft 12, which is supported in suitable frames on the under side of the platform. This shaft 5 carries a roller 13, around which is bent a strap 14. One end of the strap is connected to a lever 15, which is pivoted at one end to the frame of the platform, as at 16, and is connected at its other end to a treadle-rod 17, which extends up through the platform. The other end of the strap 14 is connected to a spring 18.

The treadle-rod is notched, as at 19, and adjacent the hole in the platform through which

the rod works is a plate 20, arranged to engage in the notches. 45

Normally the spring 18 holds the door closed. To open the door, the treadle is depressed, which by means of the strap 14 turns the roller 13 and with it the shaft on which 50 the said roller is mounted. By means of the bevel-gear this motion is communicated to the crank 8, which swings and throws the door open. If it be desired to hold the door open, the treadle is pressed laterally to engage the 55 plate 20 in one of the notches, which holds the parts as set and prevents the spring from acting. To close the door, the treadle-rod may be released by tap of the foot, when the spring 18 will pull the strap and turn the roller, shaft, 60 and crank in the opposite direction, thereby closing the door.

No hand-work is necessary to open or close the door, and the use of the invention will be found to save time, labor, and fuel and to avoid 65 cooling the furnace by leaving the door open.

What I claim as new, and desire to secure by Letters Patent, is—

The combination with a furnace-door, and a platform before the same, of a crank one arm 70 of which is connected to the door, and the other arm of which extends through the platform, a shaft geared to the crank under the platform, a laterally-movable notched treadle-rod extending through the platform, a strap 75 wound on the shaft and connected to the treadle to open the door, a spring connected to the strap, to close the door, and a plate on the platform, engageable in the notches by lateral movement of the rod. 80

In testimony whereof I have signed my name to this specification in the presence of two subscribing witnesses.

JOHN O. LAGERQUIST.
